A. J. RAY

AUTOMATIC TELEPHONE SYSTEM

Original Filed Feb. 8, 1926.

Patented Oct. 9, 1928.

UNITED STATES PATENT OFFICE.

ARTHUR J. RAY, OF CUBA, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed February 8, 1926, Serial No. 86,754 Renewed September 29, 1927.

This invention relates to automatic telephone systems in general, but more especially to automatic party line systems in which a switch, commonly known as a reverting call switch, is connected to a calling line responsive to the dialing of a certain number when the calling subscriber and the called subscriber are on the same line.

A system of this kind is shown and described in the U. S. Patent No. 1,520,268 to John Wicks. In such a system when a subscriber on a party line wishes to signal another party on the same line, he removes his receiver, dials a special number which causes a reverting call switch to be connected to the line via an individual lineswitch and one or more selector switches. After dialing the number, the calling subscriber replaces his receiver. The reverting call switch then functions to ring the bells of both the calling and the called subscriber until the called subscriber removes his receiver to answer the call, or until the calling subscriber momentarily removes his receiver, should the called subscriber fail to answer. When the called party answers, ground potential is removed from the holding conductor which causes the restoration of the reverting call switch and the other switches, the lineswitch and the one or more selectors, associated therewith. The bridge across the line at the calling and called substations causes a reoperation of the lineswitch, this switch again seizing a selector switch. The current supply for the two transmitters of the talking parties is furnished through the line relay of the last seized selector.

In the larger telephone exchange systems, especially those employing primary and secondary line switches and first and second selectors, provision may be made to give a calling subscriber a signal to indicate when he may commence dialling. This is done in order to eliminate the danger of the calling subscriber commencing to dial before the line switches have been given sufficient time to operate and prepare a first selector for operation. The common way to give this signal is to superimpose a tone current on the grounded conductor to which the line relays of the first selectors are connected. The calling subscriber hears this tone as soon as a first selector has been seized.

It at once becomes apparent that in a system supplying dial tone through the line 55 relays of the first selectors, subscribers on a party line holding conversation, one having signalled the other in the manner described above, will hear the dial tone during their entire conversation if no preventative means 60 are provided.

It is the object of this invention to provide means for preventing the dial tone from being heard by party line subscribers during conversation, in systems of this kind. 65 This is accomplished in this invention by especially equipping those second selectors which have access to the reverting call switches so that when ground potential is removed from the holding conductor at a 70 reverting call switch in use, the first selector and the line switches associated with the connection are not released, but the second selector in use disengages its wipers from the bank contacts, and permits the reverting call switch to restore to normal. The current supply for the transmitters of the talking parties is then furnished through the line relay of this second selector.

The operation of a system employing the 80 above generally described method of preventing two party line subscribers from hearing the dial tone during conversation is described fully in the following description, in so far as this invention is concerned, 85 references being had to the accompanying drawing, which is a circuit diagram of a part of an automatic telephone system embodying the invention.

In the drawing, reference character E 90 represents a first selector, E' represents a second selector and the rectangle labeled R indicates a reverting call switch which may be of the type shown and described in the above mentioned reference. The first selectors are accessible from primary line switches, or secondary line switches as the case may be, and are equipped to furnish dial tone from the dial tone machine T. In the banks of the first selectors, access is had to the various groups of second selectors. In one level of these banks access is had to special second selectors. The special second selectors as well as the regular second selectors, in turn, may have access to third selectors, or connectors, depending on the size 95 100 105

of the particular telephone system. In one level of the special second selectors, however, access is had to reverting call switches. Only when operated to this particular level 5 do the special second selectors perform any special operation. In all other levels those selectors operate just as do the regular second selectors, or the first selectors.

To describe the operation of the system illustrated and particularly the operation of the special selector, the manner in which one subscriber is signalled when another subscriber on the same party line wishes to talk to him will be considered. To initiate the 10 call, the calling subscriber removes his receiver and dials the proper number. Removing the receiver causes the lineswitch individual to that party line to operate and select a trunk to an idle first selector. If 15 secondary lineswitches are used, the primary lineswitch selects a trunk to an idle secondary lineswitch, which in turn operates to select a trunk to an idle first selector. It may be assumed that selector E is the one selected. 20 A circuit is immediately closed for the line relay 25 extending from the bridge across the line at the calling substation over the talking loop to bank contacts 16 and 17, resting contacts and armatures 18 and 19, 25 through the upper and lower windings of line relay 25, to battery and through the winding of the tone machine T to ground, respectively. The dial tone is heard by the calling subscriber indicating that he may 30 commence dialing. Relay 25 operates and prepares the selector E to receive the first digit.

The operation of a selector identical to the selector E is described in detail in the above 35 mentioned U. S. Patent No. 1,520,268. The selector E operates in response to the first digit dialed by the calling subscriber to raise its wipers opposite the proper level of bank contacts in which access is had to the special 40 second selectors, automatically rotates its wipers to select a trunk to an idle special second selector, and then extends the connection thereto. It may be assumed that the trunk selected is the one terminating in 45 the bank contacts 105-107, inclusive, extending to special second selector E'. A circuit is immediately established for the line relay 110 which extends over the subscriber's line loop through the operated lineswitches 50 to bank contacts 16 and 17, armatures 18 and 19 and their working contacts, wipers 35 and 37, bank contacts 105 and 107, conductors 108 and 109, armatures 130 and 133 and their resting contacts, through the upper and 55 lower windings of the line relay 110 to battery and ground, respectively. Line relay 110 operates and closes a circuit for release relay 111 at armature 121. Release relay 111 operates and at armature 122 places 60 ground on the holding conductor 28' thereby

grounding the bank contact 106 and the multiples thereof to mark this selector E' engaged and also to hold the selector E and the preceding lineswitches operated in the usual manner. At armature 123, a circuit 65 for the vertical magnet 117 is prepared.

In response to the impulses of the second digit dialed by the calling subscriber, line relay 110 deenergizes and again energizes a corresponding number of times. At each 70 deenergization a circuit is closed for the vertical magnet 117 which may be traced from ground at the resting contact and armature 132, armature 121 and the resting contact, armature 123 and the working contact, 75 through the winding of the series relay 112, through the winding of the vertical magnet 117 to battery. Vertical magnet 117 operates accordingly and steps the wipers 145-147, inclusive, opposite the level of bank 80 contacts in which access is had to the reverting call switches. A cam arrangement closes the shaft springs 137, these springs being closed only when the shaft is raised to this particular level in which access is 85 had to the reverting call switches. Series relay 112 is energized in series with the vertical magnet 117, and being slow acting is maintained operated during the entire vertical movement. In operating, series relay 90 112 prepares an initial energizing circuit for the stepping relay 113 at armature 124. Off-normal springs 136 are closed upon the first vertical step of the switch wipers thereby completing the circuit for the stepping 95 relay 113 which may be traced from ground by way of armature 122 and the working contact, normally closed springs controlled by armature 128, working contact and armature 100 124, closed off-normal springs 136, through the winding of the stepping relay 113 to battery. Stepping relay 113 energizes and prepares 105 a circuit for the rotary magnet 118 at armature 125, and closes a temporary locking circuit for itself at armature 126 from ground 110 at the resting contact and armature 132, working contact and armature 126, normally 115 closed interrupter contacts 135, off-normal springs 136, through the winding of relay 113 to battery.

At the end of the vertical movement series relay 112 deenergizes and closes a circuit for the rotary magnet 118 which may be traced from ground at armature 122 and the working contact, normally closed springs controlled by armature 128, normally closed springs controlled by armature 124, working contact and armature 125, through the winding of the rotary magnet 118 to battery. Relay 113 is maintained energized 120 over the temporary locking circuit after armature 124 falls back. Rotary magnet 118 operates and rotates the switch wipers 125 145-147 into engagement with the first set of bank contacts in the selected level and near 130

the end of its stroke separates the interrupter springs 135. The separation of springs 135 opens the temporary locking circuit of the stepping relay 113. Relay 113 then deenergizes and opens the circuit of the rotary magnet 118 at armature 125, and also opens another point in the temporary locking circuit at armature 126. Rotary magnet 118 deenergizes and in releasing its armature again closes the interrupter springs 135.

If the reverting call switch accessible in the first set of bank contacts is busy at this time, ground potential will be present on the private test contact engaged by the wiper 146. A circuit is then traceable from ground on the test contact engaged by the wiper 146, wiper 146, armature 131 and the resting contact, resting contact and armature 127, interrupter springs 135 which were again closed upon deenergization of rotary magnet 118, off-normal contacts 136, through the winding of the stepping relay 113 to battery. Relay 113 operates and again closes the circuit of the rotary magnet at armature 125 and again closes the temporary locking circuit at armature 126. Rotary magnet 118 again energizes and rotates the switch wiper 145-147 into engagement with the next set of bank contacts. This alternate operation of the stepping relay 113 and the rotary magnet 118 continues until the switch wipers are rotated into engagement with the bank contacts terminating a trunk to an idle reverting call switch.

It may be assumed that the reverting call switch connected to the trunk terminating in the bank contacts 38-40, inclusive, is the first idle switch accessible at this time. No ground potential will be present on the test contact 39, therefore no circuit will be closed for the stepping relay 113 when the switch wiper 146 engages the test contact 39. Since no circuit will again be closed for the rotary magnet 118, the switch wipers 145-147 will be arrested in engagement with the bank contacts 38-40, respectively. During the rotary movement of the switch wipers of selector E', ground potential was present on both ends of the winding of relay 115, ground being supplied to the upper terminal from the grounded conductor 28' by way of the normally closed springs controlled by armature 128 and the normally closed springs 138, and to the lower terminal from the grounded busy test contacts by way of the private wiper 146, armature 131 and the resting contact, resting contact and armature 127. Since ground potential is now absent from the test contact 39 engaged by the wiper 146, switching relay 115 energizes over a circuit from ground on the upper terminal of the winding of switching relay 115, through the winding of this relay, interrupter springs 135, off normal springs 136, through the winding of the stepping relay 113 to bat-

tery. The resistance of the winding of relay 115 is high enough to prevent sufficient current flow to cause the operation of the stepping relay 113 at this time. Switching relay 115 operates, however, and extends the connection to the reverting call switch by way of armatures 130 and 133 and the working contacts, wipers 145 and 147, bank contacts 38 and 40, and conductors 54 and 56 connected to the reverting call switch. Relay 115 also connects the test wiper 146 to the holding conductor 28' at armature 131; and maintains the circuit of the release magnet 116 open by disengaging armature 132 from its resting contact. By the operation of armatures 130 and 133, line relay 110 is disconnected at the resting contacts of these armatures. Relay 110 deenergizes and releases its armature. The circuit of the release relay 111 is opened, but the relay being slow acting, maintains its armatures attracted for a short interval thereafter.

By the extension of the loop connection over conductors 54-56 to the reverting call switch, a circuit for a line relay in this switch similar to the line relay 110 in the selector E' is closed. This relay operates to close a circuit for a release relay similar to the release relay 111. The operation of these relays in the reverting call switch prepares this switch to receive the next digit dialled and also places ground potential on the holding conductor 55 to maintain the selector E', the selector E, and the preceding line switches operated in the well-known manner, this taking place before the release relay 111 has had time to release its armatures and remove ground from conductor 28' and armature 122. Ordinarily the holding conductor remains extended straight through all the operated selectors and line switches, all these switches being held operated from ground supplied to this conductor from the last operated switch. In this new selector E' on this particular level (springs 137 having been closed by the movement of the switch shaft to this level), the special release relay 114 operates as soon as relay 111 restores its armature 122, and connects ground potential to the holding conductor 28' at armature 128 independent of the ground supplied from the reverting call switch over the holding conductor 55; prepares a special release circuit for the release magnet 116, which is independent of the armatures of relays 110 and 111, at armature 129; and opens a point in the test circuit at armature 127. Switching relay 115 is now maintained operated from ground on the holding conductor 55, bank contact 39, wiper 146, armature 131, and the working contact, normally closed springs 138, through the winding of relay 115, interrupter contact 135, off-normal springs 136; through the winding of the

switching relay 113 to battery. The circuits of the reverting call switch are not shown in the drawing, but particular reference is made to the one shown in the above referred to U. S. Patent, No. 1,520,268, its operation being described therein.

In response to the dialing of the next digit, the reverting call switch is operated and places its wipers on the proper set of contacts preparatory to signaling the called subscriber. After completing the dialing of the number, the calling subscriber replaces his receiver. Removing the bridge across the line causes the reverting call switch to send out the proper signaling current on the party line to alternately signal the calling and called subscribers. The signaling continues until the called subscriber removes his receiver in answer to the ringing of his bell. In response to the replacing of the bridge across the conductors of the line now connected to the reverting call switch, the reverting call switch functions to disconnect the signaling current, disconnects ground potential from the holding conductor 55, releases and restores to normal.

The removal of ground from the holding conductor 55 opens the circuit of the switching relay 115, permitting relay 115 to de-energize. Line relay 110 is again connected across the conductors 108 and 109 at armatures 130 and 133 and the resting contacts; test wiper 146 is disconnected from the holding conductor at armature 131; and a circuit is closed for the release magnet 116 at armature 132. Release magnet 116 operates to restore the switch wipers 145-147, inclusive, to normal. Since relay 110 is now bridged across the conductors 108 and 109, it again closes the circuit of the release relay 111 at armature 121. Relay 111 operates and opens the circuit for the special release relay 114 at armature 122 and the resting contact and again places ground on the holding conductor 28' and the working contact of this armature. The special release relay 114 is made slow acting to maintain the circuit of the release magnet 116 closed at armature 129 a sufficient length of time to permit the complete operation of the release magnet. With the restoration of the switch wipers to normal, the shaft springs 137 and also the springs 134 and 136 are separated as is their normal condition. The selector E' is now in its normal condition with the exception that line relay 110 and release relay 111 are operated, talking current for the transmitters of the calling and the called subscribers being supplied through the windings of the line relay 110, and the selector E and the preceding line switches being held operated in the usual manner by ground on conductor 28' supplied thereto at armature 122 and the working contact. The two sub-
scribers may now hold conversation.

At the termination of the conversation both subscribers will replace their receivers, thereby removing the bridges across the party line. The removal of these bridges opens the circuit of the line relay 110 of 70 selector E'. Relay 110 deenergizes and opens the circuit of release relay 111. Release relay 111 deenergizes and removes ground from conductor 28' at armature 122. The removal of ground from the holding conductor 28' causes the release of the selector E and the preceding lineswitches in the usual manner.

It is self evident that the selector E' will function as an ordinary second selector when operated to any level except the level at which the shaft springs 137 are closed. When the selector E' is operated to any other level, the special release relay 114 remains inoperative. With this relay in a deenergized position, the circuits in the selector E' are the same as, and function exactly as, do the circuits of the selector E and the operation is identical. It is therefore thought unnecessary to describe the operation of the selector E' when operated to any other level.

The invention, its features and operation having been described, what is thought to be new and is desired to have protected by Letters Patent is specifically stated in the appended claims.

What is claimed is:

1. In a telephone system, a first automatic switch, a second automatic switch, a third switch, means for extending a connection through the first and second switches to said third switch, means in said third switch operative responsive to the establishment of said connection for maintaining said three switches operated, means for releasing said third switch, means for releasing said second switch responsive to the release of said third switch, and means in said second switch for maintaining said first switch operated independent of said third switch.

2. In an automatic switch, a switching relay, a line relay, a release relay, a release magnet, a circuit for said release magnet including contacts on all said relays, and a second circuit for said release magnet effective responsive to an operation of said switching relay independent of said line relay and said release relay.

3. In an automatic switch, a switching relay, a line relay, a release relay, a release magnet, a circuit for said release magnet including contacts on all said relays, and a second circuit over which said release magnet is operated responsive to an operation of said switching relay independent of said line relay and said release relay, said second circuit being effective when said switch is operated to a certain level and ineffective when operated to another level.

4. In a party line telephone system, a

reverting call switch, means including a first selector and a second selector for extending a calling line to said reverting call switch in order to signal a called station on the same line, means for releasing the second selector when the called party responds, and means for preventing the release of the first selector when the called party responds.

5. In a party line telephone system, a reverting call switch, means including a first selector and a second selector for extending a calling line to said reverting call switch in order to signal a called station on the same line, means in the reverting call switch for 10 causing the release of the second selector when the called party responds, and means in the second selector for preventing the release of the first selector when the called party responds.

20 6. In a party line telephone system, a reverting call switch, means including a line switch, a first selector, and a second selector for extending a calling line to said reverting call switch in order to signal a called station 25 on the same line, and means for supplying talking current to the calling line through windings of the line relay of said second selector.

7. In a selector switch arranged to normally provide a through holding circuit between preceding and succeeding switches, a local circuit for holding the preceding switch while the selector is being operated, and means for locally closing another holding circuit to the preceding switch in case the selector is operated to a particular position.

40 8. In a selector having access to groups of trunk lines and arranged to normally provide a through holding circuit extending back from a selected trunk to a preceding switch, means for locally closing the holding circuit to the preceding switch after the selector is operated in case the selector has selected a trunk in a particular group.

45 9. In a party line telephone system, a reverting call switch, means including a first numerical switch and a second numerical switch for extending a calling line to said reverting call switch in order to signal a called station on the same line, and means for supplying talking current to the calling line through windings of the line relay of said second numerical switch.

55 10. In a party line telephone system, a line, a reverting call switch, a first selector, a second selector, connecting means for connecting said line to said first selector, means including said connecting means, said first selector, and said second selector for extending a connection from said line to said reverting call switch in order to signal a called station on the same line, and means for supplying talking current to the calling line through windings of the line relay of 60 said second selector.

11. In a telephone system, a party line, a reverting call switch, means including a first and a second selector and controlled by a calling party on said line for extending a connection from said line to said reverting call switch in order to signal a called party on said line, dial tone mechanism associated with the first selector only, means responsive to the answering of the call by the called party for releasing said reverting call switch and said second selector, and means for preventing the release of said first selector in order to prevent said dial tone mechanism from placing a dial tone on the line and interfering with the conversation.

12. In a telephone system in which a called party on a party line is signalled by a reverting call switch which is connected to the line by way of a first selector and one or more succeeding switches when a calling party on the same line wishes to converse with the called party, and in which the first selectors are provided with dial tone mechanism, the method of preventing the dial tone from interfering with the conversation which consists in preventing the release of the first selector after the called party responds while the succeeding switches of the reverting call switch are released.

90 13. In a telephone system in which connections are extended by successively operating a series of automatic switches, means for maintaining all the operated switches in position under the control of the last switch, and means in an intermediate switch operative under certain conditions for maintaining the preceding switches operated independent of the last switch.

95 14. In a telephone system in which connections are extended by successively operating a series of automatic switches and in which all switches are normally released responsive to the release of the last switch, means in an intermediate switch effective in case it is operated to a particular position for preventing the release of the preceding switches when the last switch is released.

100 15. In a telephone system in which connections are extended by successively operating a series of automatic selecting switches and in which all the switches are normally released responsive to the release of the last switch, means in an intermediate switch effective in case a succeeding switch is of a particular kind for preventing the release of the preceding switches when the last switch is released.

110 16. A telephone system in which connections are extended by successively operating a series of automatic switches and in which each switch is arranged to hold the preceding switches operated over a local circuit while it is being operated and to extend the holding circuit to a succeeding switch after it has been operated, characterized in that

means are provided in one switch which becomes effective under certain conditions for closing another local circuit for holding the preceding switches independent of the succeeding switches.

17. In a telephone system in which connections are extended by successively operating a series of automatic switches, means for holding all the operated switches in position over a through holding circuit under the control of the last switch operated, and means in an intermediate switch for separating said holding circuit into two sections so that the preceding switches are held in position under the control of said intermediate switch while said intermediate switch is held in position under the control of the last switch.

18. In a telephone system in which connections are extended by successively operating a series of automatic switches and in which each switch has a release relay which is actuated when the switch is seized by a preceding switch to maintain the preceding switch operated and is deactuated when the switch is operated to seize a succeeding switch, separate means in one switch operable under certain conditions and controlled by the release relay of the switch in its deactuated position for maintaining the preceding switch operated.

In witness whereof, I hereunto subscribe my name this fourteenth day of January, A. D. 1926.

ARTHUR J. RAY.
